SPRAY TYPE WASHING MACHINE

Lewis Dwight Bechtol, Burket, Ind.

Application March 11, 1952, Serial No. 275,963

1 Claim. (Cl. 134—57)

1 This invention relates to spray type washing machines and more particularly to a machine for washing objects, such as eggs.

It is among the objects of the invention to provide an improved spray type washing machine which is adapted to receive a basket of objects, such as eggs, and wash the objects while contained in the basket; which has an open top and a height such that loaded baskets can be conveniently placed in and removed from the machine; which directs sprays of cleaning liquid in large volume and at moderate pressure against objects in a basket disposed in the machine; which is electrically operated and substantially automatic in operation; which automatically maintains a predetermined temperature of the cleaning liquid; and which is simple and durable in construction, economical to manufacture, easy to use, and effective and efficient in operation.

Other objects and advantages will become apparent from a consideration of the following description and the appended claim in conjunction with the accompanying drawing wherein:

Figure 1 is a top plan view of a washing machine illustrative of the invention;

Figure 2 is a longitudinal cross sectional view on the line 2—2 of Figure 1; and

Figure 3 is a top plan view of a somewhat modified form of washing machine.

With continued reference to the drawing, the washing machine comprises a shell, generally indicated at 10, having an annular side wall 11 adapted to be disposed in upright position and which may be either of cylindrical shape, as illustrated in Figures 1 and 2, or of polygonal shape, as illustrated in Figure 3.

The side wall 11 is open at its upper end and its open upper end is surrounded by a rolled reinforcing bead 12 disposed at the outer side of the side wall. A bottom wall 13, of circular shape in the form of the invention shown in Figures 1 and 2, and of polygonal shape in the form shown in Figure 3, is disposed in the shell 10 at the bottom end of the latter substantially perpendicular to the longitudinal center line of the shell and is marginally connected to the side wall 11 at the bottom end of the latter. In the arrangement illustrated, the bottom wall 13 is provided with a downwardly extending marginal flange 14 and this flange and the side wall 11 are apertured to receive bolts or screws 15 by means of which the bottom wall is secured in the shell.

A partition wall 16 is disposed in the shell above and substantially parallel to the bottom wall 13 and is marginally joined to the side wall 11 by 55

suitable means, such as welding or soldering, to provide a leakproof joint between the partition wall 16 and the side wall 11 of the shell. The partition wall 16 and the portion of the side wall 11 above this partition wall together constitute a washing tank.

10 A liquid pump 17 is disposed between the bottom wall 13 and the partition wall 16 with its outlet fitting 18 substantially concentric with the center line of the shell 10 and is mounted on the bottom wall 13. In the arrangement illustrated, a base plate 19 is mounted on the bottom wall 13 at the upper side of the latter and secured to the bottom wall by suitable means, such as the bolts 20 and the base 21 of the pump is mounted on the base plate 19 and secured thereto.

20 An electric motor 22 is mounted on the base plate 19 at a location spaced from the pump 17 and the motor shaft is connected to the pump shaft by means including the flexible coupling 23 of a construction well known to the art.

25 The partition wall 16 is provided with a flanged aperture, as indicated at 24, adjacent the side wall 11 and a pipe 25 extends through this aperture and is provided at its upper end with an annular, external flange 26 which is sealed to the flange of the aperture, as indicated at 27. A flanged coupling 28 is threaded onto the pipe 25 at the bottom side of the partition wall 16, so that the flange of the aperture in the partition wall is clamped between the flange 26 and the coupling 28 to maintain a tight and leakproof joint between the pipe 25 and the partition wall 16. An elbow fitting 29 is secured to the bottom end of the pipe 25 and a pipe 30 connects the elbow fitting 29 to the inlet 31 of the pump 17 to return water from the tank 32 in the upper portion of the shell to the inlet of the pump.

30 A hollow header 33 extends through and is secured to the partition wall 16 substantially at the center of the latter, and is closed at its upper end, a pipe nipple 34 connects the open bottom end of the header 33 to the outlet 18 of the pump 17, so that water or other cleaning liquid returned to the pump through the pipes 25 and 30 is forced by the pump through the pipe nipple 34 into the header 33.

35 A plurality of spray pipes, as generally indicated at 35, are disposed in the tank 32, each of these pipes being of rectangular shape and having two legs, as indicated at 36 and 37, disposed substantially at right angles to each other. The leg 36 of each spray pipe is connected at its distal end to the header 33 and these legs of the several spray pipes radiate from the header 33 toward

the side wall 11 of the tank at substantially equal angular intervals around the header and spaced from and substantially parallel to the partition plate 16. The legs 37 of the several spray pipes extend upwardly from the proximal ends of the legs 36 and upstand along and spaced from the inner surface of the side wall 11. The legs 37 terminate short of the top end of the side wall 11 and are closed at their upper ends by suitable means, such as the screw plugs 38.

In the arrangement illustrated in the drawing, there are six spray pipes spaced apart at angular intervals of approximately 30 degrees around the header 33, but it is to be understood that a different number of spray pipes spaced apart at different angular intervals can be used, if desired, without in any way exceeding the scope of the invention.

The legs 36 of the spray pipes are provided in their sides remote from the partition wall 16 with apertures 39 spaced apart longitudinally of the corresponding legs 36 of the pipes and in the legs 37 with apertures 40 spaced apart longitudinally of the corresponding legs 37, and in the sides of these legs remote from the side wall 11. These apertures 39 and 40 direct sprays or jets of cleaning liquid upwardly and inwardly of the bottom 15 and side wall 11 of the tank 32, the apertures being of such size and of such number and the pump 17 being of such capacity that the liquid is delivered in large volume and at a moderate pressure.

An electric heater 41 is disposed above the partition wall 16 and is mounted at one end in an aperture provided in the partition wall 16 by a suitable fitting 42. A second fitting 43 is also mounted in an aperture in the partition wall 16 adjacent the fitting 42 and connected to the heater 41. A thermostat 44 is disposed in the tank 32 and mounted at one end in an aperture in the partition wall 16 by a fitting 45 and a switch 46 is mounted on the inner side of the side wall 11 below the partition wall 16 and the thermostat 44 is connected to this switch 46 to operate the switch. The thermostatic switch 46 can be set for a predetermined temperature by a handknob 47 mounted on a shaft extending from the switch 46 through an aperture in the side wall 11 and a wire 48 extends from the switch 46 through the fitting 42 and is connected to one side of the heater element in the heater 41. One wire 49 of a two-wire extension cord 50 extends through the fitting 43 and is connected to the other side of the heater element in the heater 41, while the other wire 51 of the extension cord 50 is connected to the other side of the switch 46 from that to which the wire 48 is connected.

With this arrangement, the thermostat 44 controls the heater 41 through the switch 46 to maintain cleaning liquid in the lower portion of the tank 32 substantially at a temperature selected by the thermostat adjusting handknob 47.

The wires of the extension cord 50 are branched and led through a manually operated switch 52 to the electric motor 22, so that operation of the motor is manually controlled. If desired, however, the operation of the motor may also be controlled by the thermostatic switch 46, so that the motor cannot be placed in operation unless the cleaning liquid in the tank 32 is at a predetermined temperature.

Except for having a side wall, as indicated at 55, a bottom wall and a partition wall, as indicated at 56, of polygonal shape, the modified

form of the invention shown in Figure 3 is the same as that illustrated in Figures 1 and 2 and described above.

In the use of the device, with the cleaning liquid at the proper temperature and the pump 17 in operation, an open-work basket, such as the wire mesh basket 51, loaded with eggs or other objects to be cleaned, is placed in the tank 32 between the upstanding arms 37 of the spray pipes 35 and left in position until the spray, forced through the basket and between the articles therein from the apertures 39 and 40 in the spray pipes, has sufficiently cleaned the articles, whereupon the basket is lifted out of the upper end of the tank and, if desired, another loaded basket placed in the machine.

The invention may be embodied in other specific forms without departing from the spirit or essential characteristics thereof. The present embodiments are, therefore, to be considered in all respects as illustrative and not restrictive, the scope of the invention being indicated by the appended claim rather than by the foregoing description, and all changes which come within the meaning and range of equivalency of the claim are, therefore, intended to be embraced therein.

What is claimed is:

A spray type washing machine comprising a shell adapted to be disposed in upright position and having an annular side wall and an open upper end, a partition wall in said shell disposed substantially perpendicular to the longitudinal center line of the shell and marginally joined to said side wall intermediate the height of the latter, said partition wall and the portion of said side wall above said partition wall constituting a tank, a motor driven pump disposed in said shell below said partition wall, a pipe secured at one end to said partition wall and extending through the latter and connected at its other end to the inlet of said pump, a header extending through said partition wall substantially centrally thereof and having its upper end closed and its lower end connected to the outlet of said pump, and spray pipes of right angular shape connected each at one end to said header and having portions radiating from said header toward said side wall at substantially equal angular intervals and portions upstanding along the inner side of said side wall, said spray pipes having their ends remote from said header closed and having perforations spaced apart longitudinally thereof for directing liquid spray upwardly from said partition wall and inwardly from said side wall, a heater disposed in said tank adjacent said partition wall, a thermostat extending through said partition wall into said tank, and a switch actuated by said thermostat and controlling said heater to maintain liquid in said tank substantially at a predetermined temperature, said side wall being of polygonal shape and said partition wall also being of polygonal shape and closely fitting the interior of said side wall.
